(57) **CLAIM**

The ornamental design for a terminal device as shown and described.

DESCRIPTION

FIG. 1 is a front elevation view of a first embodiment of a terminal device;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof;

FIG. 8 is a front elevation view of the first embodiment of the terminal device, shown in a first folded state;

FIG. 9 is a rear elevation view thereof;

FIG. 10 is a left side elevation view thereof;

FIG. 11 is a right side elevation view thereof;

FIG. 12 is a top plan view thereof;

FIG. 13 is a bottom plan view thereof;

FIG. 14 is a perspective view thereof;

FIG. 15 is a front elevation view of the first embodiment of the terminal device, shown in a second folded state;

FIG. 16 is a rear elevation view thereof;

FIG. 17 is a left side elevation view thereof;

FIG. 18 is a right side elevation view thereof;

FIG. 19 is a top plan view thereof;

FIG. 20 is a bottom plan view thereof;

FIG. 21 is a perspective view thereof;

FIG. 22 is a front elevation view of the first embodiment of the terminal device, shown in a third folded state;

FIG. 23 is a rear elevation view thereof;

FIG. 24 is a left side elevation view thereof;

FIG. 25 is a right side elevation view thereof;

FIG. 26 is a top plan view thereof;

FIG. 27 is a bottom plan view thereof;

FIG. 28 is a first perspective view thereof;

(Continued)

FIG. 29 is a second perspective view thereof;
 FIG. 30 is a front elevation view of the first embodiment of the terminal device, shown in a fourth folded state;
 FIG. 31 is a rear elevation view thereof;
 FIG. 32 is a left side elevation view thereof;
 FIG. 33 is a right side elevation view thereof;
 FIG. 34 is a top plan view thereof;
 FIG. 35 is a bottom plan view thereof;
 FIG. 36 is a first perspective view thereof;
 FIG. 37 is a second perspective view thereof;
 FIG. 38 is a front elevation view of a second embodiment of the terminal device;
 FIG. 39 is a rear elevation view thereof;
 FIG. 40 is a left side elevation view thereof;
 FIG. 41 is a right side elevation view thereof;
 FIG. 42 is a top plan view thereof;
 FIG. 43 is a bottom plan view thereof;
 FIG. 44 is a perspective view thereof;
 FIG. 45 is a front elevation view of the second embodiment of the terminal device, shown in a first folded state;
 FIG. 46 is a rear elevation view thereof;
 FIG. 47 is a left side elevation view thereof;
 FIG. 48 is a right side elevation view thereof;
 FIG. 49 is a top plan view thereof;
 FIG. 50 is a bottom plan view thereof;
 FIG. 51 is a perspective view thereof;
 FIG. 52 is a front elevation view of the second embodiment of the terminal device, shown in a second folded state;
 FIG. 53 is a rear elevation view thereof;
 FIG. 54 is a left side elevation view thereof;
 FIG. 55 is a right side elevation view thereof;
 FIG. 56 is a top plan view thereof;
 FIG. 57 is a bottom plan view thereof;
 FIG. 58 is a perspective view thereof;
 FIG. 59 is a front elevation view of the second embodiment of the terminal device, shown in a third folded state;
 FIG. 60 is a rear elevation view thereof;
 FIG. 61 is a left side elevation view thereof;
 FIG. 62 is a right side elevation view thereof;
 FIG. 63 is a top plan view thereof;
 FIG. 64 is a bottom plan view thereof;
 FIG. 65 is a first perspective view thereof;
 FIG. 66 is a second perspective view thereof;
 FIG. 67 is a front elevation view of the second embodiment of the terminal device, shown in a fourth folded state;
 FIG. 68 is a rear elevation view thereof;
 FIG. 69 is a left side elevation view thereof;
 FIG. 70 is a right side elevation view thereof;
 FIG. 71 is a top plan view thereof;
 FIG. 72 is a bottom plan view thereof;

FIG. 73 is a first perspective view thereof; and,
 FIG. 74 is a second perspective view thereof.
 The broken lines are included for the purpose of illustrating portions of the terminal device that form no part of the claimed design.
